UNITED STATES PATENT OFFICE.

WILLIAM A. BUCHANAN, OF ASHEVILLE, NORTH CAROLINA.

THILL-COUPING.

1,073,328.

Specification of Letters Patent.

Patented Sept. 16, 1913.

Application filed January 10, 1913. Serial No. 741,358.

To all whom it may concern:

Be it known that I, WILLIAM A. BUCHANAN, citizen of the United States, residing at Asheville, in the county of Buncombe and State of North Carolina have invented certain new and useful Improvements in Thill-Couplings, of which the following is a specification.

This invention relates to thill couplings, 10 and more particularly to that class of thill couplings known as antirattlers.

It is one object of the present invention to provide a thill coupling so constructed that the thill may be readily connected with and disconnected from the same and without the use of tools of any sort, and which will when in use securely hold the thill iron and not be likely to accidentally release the same.

The thill coupling embodying the present 20 invention is of that type in which the thill iron includes a bearing element which is confined within a socket carried by the axle, by means of a cap, and it is one aim of the invention to so form and assemble the socket and cap that no strain whatsoever will be imposed upon the cap while the device is in use.

Another aim of the invention is to provide 30 means for holding the cap closed, which means may be adjusted so as to exert a greater or less pressure upon the cap.

Another aim of the invention is to provide 35 means for securely holding the cap against lateral displacement which would tend to weaken its hinge connection with the socket member which it closes.

For a full understanding of the invention reference is to be had to the following description and accompanying drawing in 40 which:

Figure 1 is a perspective view of the thill coupling embodying the present invention. Fig. 2 is a vertical sectional view taken in a plane from front to rear, the coupling being shown closed. Fig. 3 is a view similar to Fig. 2 but showing the coupling partly opened. Fig. 4 is a plan view of the coupling. Fig. 5 is a vertical transverse sectional view on the line 5—5 of Fig. 2, looking in the direction indicated by the arrows.

Corresponding and like parts are referred to in the following description and indicated in all the views of the accompanying drawings by the same reference characters.

In the drawings the axle is indicated by the numeral 1 and has fitted to it a clip 2 in-

cluding the usual threaded arms 3. The coupling includes a body member 4 which constitutes the clip-plate it being provided with openings through which the threaded ends 60 of the arms 3 project, as in the ordinary clip-plate. Nuts 5 are threaded onto the arms 3 and bear against the under side of the body 65 4 and serve to hold the body firmly in place against the under side of the axle. The body 4 is extended forwardly to form a head 6 which is relatively thick and which has its upper side inclined downwardly and rearwardly as indicated at 7. The head 6 is formed with a socket 8 which is approximately semi-spherical and of a depth nearly equal to its diameter. The body at its opposite sides, or more specifically the wall of the socket 8 is formed at diametrically opposite points with recesses 9 which communicate with the socket and open at the lateral faces of the said body. The bottom wall of each recess 9 is substantially semi-circular in extent and the rear wall extends substantially tangentially with respect to 80 the bottom wall, as clearly shown in Fig. 3, and as indicated at 10. The forward wall 11 of the socket extends substantially parallel to the rear wall thereof and it will be observed by referring to the said Fig. 3 that 85 both walls are inclined upwardly and rearwardly. The purpose of this construction will presently be fully set forth.

Disposed removably within the socket 8 is a substantially semi-spherical packing 12 90 which may be of leather or any other suitable material.

The thill is indicated by the numeral 13 and the thill-iron by the numeral 14, the iron being secured upon the under side of the 95 thill in the usual manner will be provided at its rear end with spaced arms 15 which extend substantially in parallel relation and which straddle the head 6 in a manner shown in Figs. 1, 4 and 5 of the drawing, when the 100 thill-iron is connected with the coupling. The thill-iron carries a bearing element consisting of a spherical head 16 provided with trunnions 17 which project therefrom at diametrically opposite points and are secured at their ends in openings in the ends of the arms 15 of the thill-iron. The spherical head 16 is adapted to be fitted within the packing 12 in the socket 8 in a manner shown in Fig. 2 and it will be observed by 110 referring to the said figure that the axis of the head is located a distance below the plane

occupied by the upper side of the head 6, substantially equal to the radius of the head 15 so that nearly the entire surface of the head 16 will be received by the wall of the 5 socket 8 or more specifically the packing 12 arranged within the said socket. At this point it will be apparent that inasmuch as the line of draft is substantially horizontal the head 16 will have firm bearing against 10 the forward side of the socket when a pull is exerted upon the thill. It will furthermore be apparent that inasmuch as the walls 11 of the recesses 9 are inclined upwardly and rearwardly, the trunnions will, between 15 the head 16 and arms 15, bear firmly against the said walls and thereby insure against accidental disengagement of the head 16 and trunnions from the socket and the recesses.

The socket 8 is closed by means of a cap 18 formed with spaced ears 19 receiving between them an ear 20 upon the head 6, a pivot pin 21 being engaged through the ears 19 and 20 whereby to connect the cap 18 with the head 6 for swinging movement. 20 The cap 18 is formed in its under side with a recess 22 which is formed to fit the upper side of the head 16 in a manner clearly shown in Fig. 2. It will be observed that the cap 18 is pivoted at the forward side of the head 6 and when in closed position overlies the inclined upper face 7 of the said head and has its rear end located adjacent to the forward end of the clip arms 3. In its upper side and adjacent its said rear end, the cap 35 18 is formed with a transversely extending groove 23 and at a point substantially midway between the ends of the groove with an opening 24 in communication with the groove. A stud 25 is provided upon the upper side of the head 6 and the upper end of 40 this stud, when the cap 18 is in closed position, fits in the opening 24, as shown in Fig. 2 and serves to brace the cap against lateral displacement.

45 As a means for holding the cap in closed position, or in other words in the position shown in Fig. 2, there is provided a yoke which engages over the cap and which is caused to exert pressure against the cap by means of a spring. The yoke is illustrated 50 as including spaced sides 26 and connecting ends 27 and 28. The sides 26 are bent midway between the ends so that the portions at opposite sides of their bends extend at an obtuse angle to each other as shown in Figs. 55 1, 2 and 3. The yoke straddles the body 4 and its head 6 and the connecting end 27 of the yoke fits within the groove 23 in the upper sides of the cap 18. A block 29 is 60 provided with a threaded stud 30 which projects from its upper side and which is adjustably threaded into a socket 31 in the under side of the body 4. The block 29 is provided with laterally projecting pintle lugs 32 located upon its opposite side faces

and it is to these lugs and to the connecting end 28 of the yoke that the ends of the leaves of the spring above mentioned are connected. One leaf of the spring is indicated by the numeral 33 and the other by the numeral 34 and the leaf 33 is bifurcated at its end and its furcations are bent to form pintle eyes 35 which receive the pintle lugs 32. In a like manner the end of the leaf 34 is bent upon itself to form a sleeve 36 receiving the connecting end 28 of the yoke. The spring is bent between its ends upon itself as indicated at 37, to form the leaves 33 and 34 and the leaf 33 adjacent the bend 37 is curved downwardly and rearwardly as indicated at 38. In a similar manner the leaf 34 adjacent the said bend is curved downwardly and rearwardly as at 39. By referring to Fig. 2 of the drawing it will be seen that the leaf 33 is of greater length than the leaf 34 and is located above the said leaf, considering the spring to be in position to exert a downward pull upon the bail which engages the cap 18. It will also be apparent that both leaves are inclined downwardly and forwardly but that the inclination of the leaf 34 is greater than that of the leaf 33 so that the said leaves may be said to diverge in a forward and downward direction. It will further be seen by reference to the said figure that the leaf 33 extends between the sides 26 of the yoke and that it bears at its bend 38 against the lower end of the respective clip-arm 3 or against the nut 5, 90 depending of course upon whether or not the arm projects below the nut. It will now be apparent that when the spring is swung to the position shown in Fig. 2 the pivot 28 will be located rearwardly of the pivot 32 105 and inasmuch as the leaves 33 and 34 have a tendency to spring apart, a downward pull will be exerted upon the yoke, whereby to yieldably although firmly hold the cap 18 in closed position. It is to be noted that due 110 to the bend in the side members 26 of the yoke, the pull exerted by the spring will tend to straighten out the said sides, but this tendency will be yieldably resisted, thereby increasing the resiliency of the device as a 115 whole. It will be seen that the point of engagement of the leaf 33 with the clip arm is at the forward end of the curved portion 38 of the said leaf so that this portion of the leaf and the bend 37 form a finger-piece 120 projecting rearwardly beyond the clip and body 4 in position for engagement by the hand for the purpose of swinging the spring downwardly and forwardly to open the coupling. When the spring is so swung it will 125 assume about the position shown in Fig. 3 of the drawing and after having assumed such a position, the connecting end 27 of the yoke may be disengaged from the groove 23 in the cap 18 and the cap may be swung 130

upwardly to permit of disengagement of the head 16 from the socket 8.

It will be apparent by reference to Figs. 2 and 3 that the bend 39 in the leaf 34 constitutes a finger-piece or hook in the concavity of which the finger may be engaged for the purpose of swinging the spring upwardly and rearwardly to assume the position shown in Fig. 2. It will further be apparent that inasmuch as the leaf 34 of the spring is inclined downwardly and forwardly, to the degree shown in the drawing, a downward thrust will be exerted against the yoke which will serve to more firmly and securely lock the parts in position and will furthermore add to the resiliency of the spring and render it less liable to become weakened. In fact, in all similar structures, so far as I am aware, the leaves 20 of the spring corresponding to the spring herein shown and described, extend parallel so that the spring is not capable of exerting a downward thrust upon the yoke as in the instance of the present invention, 25 when the parts are in locked position.

As before stated, the stud 30 is threaded adjustably into the socket 31, and consequently should the spring become weakened, the yoke may be passed over the head 6 and the block 29 may be rotated so as to unthread the stud a short distance which will, as a consequence, lower the pintle lugs 32 and increase the tension on the spring when restored to position for use. In order that the head 16 and the packing 12 may be lubricated the wall of the socket 8 in the rear is formed with an opening 40 in which is inserted a piece of wick or felt indicated by the numeral 41. One end of 35 this lubricant conducting element projects into the socket 8 and preferably rests against the head 16 and the other end projects a slight distance exteriorly of the socket so that it may readily receive lubricant from the spout of an oil can.

From the foregoing description of the invention it will be seen that there is provided a simple but highly efficient thill coupling and one which will not be liable

to become disarranged or unfastened, although it may be readily manipulated, so as to confine or release the bearing element of the thill coupling. It will further be seen that inasmuch as the forward side of the head 16 is received by the wall of the socket 8, or more specifically by the packing 12, the forward pull exerted upon the thills will be borne practically entirely by the fixed head 6 so that no strain will be imposed upon the cap 18.

Having thus described the invention what is claimed as new is:

1. In a thill coupling of that type including a socketed body-member and a cap-member supported thereby in position to close the socket, a head having a stem adjustably threaded into the body-member, a bowed leaf-spring having pivotal connection with the head at one end, and a yoke connected at the other end of the spring and engaged with the cap-member, adjustment of the head serving to adjust the tension of the spring whereby to cause the yoke to bear more or less firmly upon the cap-member.

2. In a thill coupling of that type including a socketed body member and a cap member supported thereby in position to close the socket, a head having a stem adjustably threaded into the body member and provided with oppositely projecting studs, a bowed leaf-spring bifurcated at one end and having its furcations pivotally fitted about the said studs and straddling the head, and a yoke connected at the other end of the spring and engaged with the cap member, the head being adapted to be rotated upon rotation of the spring whereby to adjust the tension of the spring and cause the yoke to bear more or less firmly upon the cap member.

In testimony whereof I affix my signature in presence of two witnesses.

WILLIAM A. BUCHANAN. [L.S.]
